H. C. Linslaff
Attorney.

UNITED STATES PATENT OFFICE.

WILLIAM J. STOOP, OF WHEELING, WEST VIRGINIA.

BAFFLE SUPPORT FOR WATER-TUBE BOILERS.

Application filed December 23, 1921. Serial No. 524,448.

To all whom it may concern:

Be it known that I, WILLIAM J. STOOP, a citizen of the United States of America, and resident of Wheeling, county of Ohio, State 5 of West Virginia, have invented certain new and useful Improvements in Baffle Supports for Water-Tube Boilers, of which the following is a specification.

This invention relates broadly to water- 10 tube boilers of the Stirling type, and more specifically to means for supporting the baffle walls of such boilers.

The primary object of the invention is to provide, in a water-tube boiler, a simple and improved means of support for the usual baffle walls whereby the passage of the heated gases and products of combustion are guided and deflected in their course with respect to the tubes.

As boilers of this type have heretofore been constructed, it has been the practically universal practice to support certain of the baffle walls by resting the lower ends thereof upon clamps attached at suitable points to 20 certain of the boiler tubes. These clamps are objectionable as supports for various reasons, chief among which may be mentioned that, due to the expansion and contraction which results from wide variations of temperature to which they are subjected, said clamps work loose and shift out of position to the extent that it is practically impossible to maintain them in their normal horizontally aligned relation for any considerable 30 length of time.

It is the aim of the present invention to provide a form of mounting which will serve to permanently support the baffle walls in their proper positions.

In describing the invention in detail, reference is herein had to the accompanying drawings, in which—

Figure 1 is a longitudinal section of a boiler equipped with my invention; and—

Figure 2 is a transverse section of the same taken substantially on line 2—2, Fig. 1, with the boiler tubes and baffles omitted to more clearly illustrate my invention.

Referring to said drawings, 1 and 2 indicate, respectively, the second and third banks of tubes of the boiler, and 3 and 4 designate baffles or baffle walls associated with said banks for guiding and deflecting the course of the gases and products of combus-

tion with respect to said banks in their passage from the furnace 5 to the stack-outlet 6.

Each of said baffles 3 and 4 rests in an inclined position against certain rows of the tubes in said banks 1 and 2 and has its lower end seated upon a transversely disposed horizontal member 7 which may be in the form of a bar or rod, but is preferably in the form of a metal pipe, as shown. Each pipe 7 is suspended intermediate its ends by one 65 or more metal rods 8 which have terminal hooks or eyes 9 formed on their lower ends, said hooks or eyes being disposed in embracing relation to said pipe. Said rods 8 depend from a suitable overhanging support, 70 such support being preferably constituted by parallel I-beams 10 upon which is carried, as ordinarily, the usual cross-baffle 11. It will be understood that other forms of support for the rods may be employed and 75 that, therefore, I do not desire to confine myself exclusively to the use of the I-beam support shown, which latter is preferred simply for the reason that it is conveniently located for the purpose and its use avoids 80 the necessity of introducing other means of support for said rods.

The upper ends of the rods 8 are threaded and directed through short plates or channel sections 12 which are interposed between 85 the I-beams 10 with their opposite ends seated upon the adjacent base flanges of said I-beams. Nuts 13 threaded upon said rods rest upon said plates 12 for supporting the rods, as shown.

It is preferred that pipes, rather than rods, constitute the baffle seating members 7, and also that the opposite ends of said pipes be extended outward through the side walls 14 of the boiler, thus permitting cool 95 air to circulate through the pipes for cooling purposes.

What is claimed is—

1. In a water-tube boiler, the combination with an inclined baffle for guiding and deflecting the products of combustion with respect to the banks of water-tubes, of a mounting for said baffle comprising a horizontally disposed pipe arranged in underlying supporting relation to the lower end of 100 said baffle, said pipe having its ends opening outward through the side walls of the boiler, and suspension rods by which said pipe is 105

carried, said rods being attached to a stationary supporting member occupying an elevated position within the boiler.

2. In a water-tube boiler, the combination with inclined baffles for guiding and deflecting the products of combustion with respect to the banks of water tubes, and I-beam supports for a cross-baffle, of supporting means for said inclined baffles, said means comprising horizontally disposed pipes upon which the lower ends of said baffles are seated, said pipes having their opposite ends projecting outward through the side walls of the boiler, and suspension rods depending from said I-beam supports and having their lower ends in supporting relation to said pipes.
3. In a water-tube boiler, the combination with inclined baffles for guiding and deflecting the products of combustion with

respect to the banks of water tubes, and I-beam supports for a cross-baffle, of supporting means for said inclined baffles, said means comprising horizontally disposed pipes upon which the lower ends of said baffles are seated, said pipes having their opposite ends projecting outward through the side walls of the boiler, and suspension rods depending from said I-beam supports, said rods having eyes formed on their lower ends and having said pipes directed through said eyes.

In testimony whereof, I affix my signature in presence of two subscribing witnesses.

WILLIAM J. STOOP.
